UNITED STATES PATENT OFFICE

94,077

DESIGN FOR A HOP SCOTCH GAME DEVICE

Muriel B. Eddy, Green Bay, Wis.

Application June 29, 1934, Serial No. 52,382

Term of patent 7 years

To all whom it may concern:

Be it known that I, Muriel B. Eddy, a citizen of the United States, residing at Green Bay, county of Brown and State of Wisconsin, have invented a new, original, and ornamental Design for a Hop Scotch Game Device of which the following is a specification, reference being had to the accompanying drawing, forming a part thereof.

The figure is a perspective view of a hop scotch game device, showing my new design.

I claim:

The ornamental design for a hop scotch game device, as shown.

MURIEL B. EDDY.
